TRAVICE N. DE WITT, OF BALTIMORE, MARYLAND.

CUE-TIP FASTENER.

1,028,002.

Specification of Letters Patent.

Patented May 28, 1912.

Application filed January 29, 1912. Serial No. 674,031.

To all whom it may concern:

Be it known that I, TRAVICE N. DE WITT, a citizen of the United States, residing at Baltimore, in the State of Maryland, have 5 invented certain new and useful Improvements in Cue-Tip Fasteners; and I do declare the following to be a full, clear, and exact description of the invention, such as will enable others skilled in the art to which 10 it appertains to make and use the same.

This invention relates to games and toys, and more especially to billiard devices; and the object of the same is to produce an improved cue tip fastener.

15 To this end the invention consists in the details of construction hereinafter more fully described and as shown in the drawings wherein—

Figure 1 is a central vertical longitudinal 20 section of the tip of a billiard cue, showing this improved fastener with all its parts assembled. Fig. 2 is a perspective detail of the grapple. Fig. 3 is a perspective detail of the cue-tip. Fig. 4 is a perspective view 25 of the lining sleeve or tube.

In the drawings the letter C designates the smaller end of a wooden cue to which is ordinarily attached a leather tip, and in the present case the letter L designates a leather 30 button cemented or otherwise secured to a fiber disk F and both being accurately ground or otherwise formed on their periphery so that they shall be circumferentially of the same size as the smallest part of the 35 cue tip C.

My improved fastener is designed for the purpose of holding the tip (which comprises the leather and the fiber) removably upon the end of the cue, so that when the 40 former becomes worn or hardened in use it can be detached and replaced by a new one.

Coming now more particularly to the present invention, the fastener proper consists of two principal parts of metal which 45 I will call respectively the sleeve and the grapple. The sleeve comprises a short tube 1 of a size to permit it to be inserted into a tubular bore 2 which is formed in the end of the cue tip C, and of less length than the 50 depth of said bore so that it will not extend completely to the bottom of the same; and a nut 3 which is brazed or otherwise secured, or possibly formed integral within, the inner end of said tube so that the tube and 55 the nut are practically one member consti-

tuting the sleeve. I preferably punch indentations 4 in the wall of the tube near the outer end of the same, so that the burs 5 thereof are driven outward into the wood of which the cue tip is composed, and the sleeve 60 is thereby held rigidly within the bore 2. The other member of this improved fastening is called a grapple because its function is to grab the tip removably. It comprises a fork 10 preferably having at least three 65 arms, and the tips 11 of the latter are in-turned obliquely as shown so that they may enter slots 12 properly disposed in the inner face of the fiber disk F and all by preference converging slightly toward its center; and the crotch of the fork is secured to or continued integrally into a screw 13 whose threads are such that it is adapted to engage those within the nut 3. The proportion 70 of parts relative to that of the part of the other member is such that before the shoulder 14 at the base of the fork strikes upon the upper end of the nut 3 the mouth 6 of the tube 1 contacts with the outer side of the fork-arms and the latter are therefore 75 forced axially inward, with the result that their tips 11 are positively forced into the slots 12 and the cue tip is held reliably in place with the edge of the rear face of the fiber disk F contacting at 20 with the extremity of the cue tip C around the bore 80 therein. This I consider an important feature of my invention, for the reason that in a large proportion of shots the tip of the cue is directed at one edge against the ball being 85 shot, and the reliable annular contact at 20 between the fiber disk and the end of the cue greatly assists the player in making such shots, which are called "English" 90 shots because they spin the ball as it is projected forward. When plain shots are made, however, where the center of the cue tip impinges against the face of the ball, a certain yielding action to the tip is permitted by 95 reason of the fact that its center is not rigidly supported, and in fact is not materially stiffened by the fiber disk F. Therefore the use of a tip secured in this manner gives the player the option of making a shot with that part of the tip which stands solidly over 100 the wall of the cue or that part of it which stands over the cavity within its bore, and in neither case will the shot interfere with the engagement of the tips 11 of the grapple. 105 In practice the cue is furnished the user 110

with a number of the tips which are preferably ground to the same size as the smaller end of the cue, although this detail is not absolutely necessary, but the rear face of each 5 fiber disk F is provided with the oblique slot 12 as described. When now it becomes desirable to replace the cue tip for any reason, it is necessary only to grasp it between the thumb and finger and rotate it bodily to 10 the left with respect to the cue; this movement carries the tips 11 of the fork-arms 10 around with the cue tip, and the screw 13 is slowly withdrawn from the nut 3, the back of the fork-arms gradually moving off the 15 mouth 6 of the tube 1 until their tips 11 automatically spring apart and disengage the slots 12 in the fiber disk F. The imperfect cue tip is then thrown away and another put in its place, its slots 12 engaged 20 with the tips 11 on the fork-arms 10, and the entire grapple is put into position within the sleeve in a manner described above. As the cue tip is rotated to the right it turns 25 the grapple with it and the engagement of the screw 13 with the nut 3 draws both the grapple and tip downward until the back of the fiber disk contacts firmly at 30 with the end of the cue C, by which time the fork-arms have been borne reliably inward and the cue tip is held upon their tips 11 as shown.

Thus it will be seen that I have produced a cue tip fastener which is extremely simple and strong, and which holds the cue tip 35 upon the cue in such manner that these two

parts stand in reliable contact around their edges with the advantage set forth above.

I do not limit myself to the precise details of construction, further than as set forth in the appended claim, and the materials and 40 proportions of parts may be left to the manufacturer.

What is claimed as new is:

The herein described cue-tip fastener comprising a cue having a socket bored in its 45 extremity, a tubular sleeve fitting closely within the same and having near its mouth outwardly projecting indentations punched through its body and into the wooden shell of the cue, a nut fast within the inner end 50 of said sleeve, and a grapple having a screw at its inner end engaging said nut and a plurality of normally divergent fork-arms at its outer end provided with obliquely in-turned tips; combined with the cue-tip 55 proper including a leather face mounted on a fabric disk of a size to cover the end of the cue and rest on the extremity of its wall, the inner face of said disk being provided with slots converging toward the leather and disposed so as to receive the tips of said fork-arms, all as and for the purpose set forth.

In testimony whereof I have hereunto set my hand in presence of two subscribing witnesses.

TRAVICE N. DE WITT.
